UNITED STATES PATENT OFFICE.

JOHN D. MCRAE, OF BALDWINSVILLE, NEW YORK.

HOSE-CLAMP.

SPECIFICATION forming part of Letters Patent No. 453,359, dated June 2, 1891.

Application filed July 28, 1890. Serial No. 360,163. (No model.)

To all whom it may concern:

Be it known that I, JOHN D. MCRAE, of Baldwinsville, in the county of Onondaga, in the State of New York, have invented new and useful Improvements in Hose-Clamps, of which the following, taken in connection with the accompanying drawings, is a full, clear, and exact description.

My invention relates to hose-clamps.

10 My object is to provide a hose-clamp for the purpose of coupling pieces of hose together by clamping them to a common metallic tube, or for the purpose of securing the end of the hose to the hose-nozzle, simple and cheap of construction, and of great utility.

15 My invention consists of the several novel features of construction and operation hereinafter described, and specifically set forth in the claim, hereto annexed.

20 It is constructed as follows, reference being had to the accompanying drawings, in which—

Figure 1 is a side elevation of a piece of the hose secured by my clamp to a metallic 25 coupling-tube. Fig. 2 is a top plan view thereof, showing the clamping-hose and means for securing them together. Fig. 3 is a side view of the clamp complete detached. Fig. 4 is a vertical section thereof. Fig. 5 is 30 a side elevation of the clamping-wire detached. Fig. 6 is a top plan view thereof. Fig. 7 is an isometrical elevation of one of the clamp-heads. Fig. 8 is a view of its inner face, showing a recess for the reception 35 of the twisted ends of the clamping-wire.

Similar letters and figures of reference indicate corresponding parts.

A is the hose.

B is a metallic coupling-section or end of 40 a hose-nozzle, upon one end of which the hose is secured by the clamp, being also provided with corrugations 1, over which the hose fits. The clamping-band 2 consists of a single wire bent centrally, so as to create a 45 cross-bar, and extending thence at right angles to a cross-bar formed at the other end by bending the ends of the wires inwardly toward each other, meeting substantially midway, then twisted together and the twisted 50 ends 3 standing at about a right angle to these inwardly-bent portions, which constitute the cross-bar at the other end of the loop

thus created. This loop is then bent to substantially the circle of the exterior of the hose, the loop thus forming a double band of 55 two rings connected by the cross-bars, the twisted ends projecting across the space between the bars. The clamping-heads 4 consist of a base concaved to fit upon the periphery of the hose and a body projecting 60 outward from the base and of less width, so as to leave a flange 6 along its lower edge and having a concave across its front substantially in line with the top of the flange. A bolt-hole a is also provided through the 65 outer end of the body, and the outer face is suitably recessed or countersunk to receive a screw or bolt head or a nut; also, one head is provided with a recess 5 extending back in the cavity of the base longitudinally and 70 adapted to receive the twisted ends of the wire. The heads are inserted into the band, so that each cross-bar fits in the groove across the inner face of the body, and the wire rings extend back over the flanges 6 on both sides, 75 and 7 is a bolt inserted through the heads, and when this is screwed up the cross-bars of the band are drawn in toward each other, and the twisted ends of the wire are forced still farther into the recess in the head, and 80 most of this twist will lie upon the hose and constitute a band across the intervening space between the heads.

It will thus be seen that I create a double clamping-band from a single piece of wire 85 and tighten the whole by a single bolt.

What I claim as my invention, and desire to secure by Letters Patent, is—

A wire clamping-band composed of a single piece of wire bent to form a rectangle and 90 having the ends of the wire secured together in one of the end bars of the rectangle and projecting beyond it, in combination with concaved clamping-heads detachably connected to the end bars of the rectangle and 95 grooved to receive the ends of the wire, and means for securing the heads together.

In witness whereof I have hereunto set my hand this 23d day of July, 1890.

JOHN D. MCRAE.

In presence of—

H. P. DENISON,
E. V. MACK.
